United States Patent Office.

MARTIN VAN BUREN HOWE, OF GARDNER, MASSACHUSETTS, ASSIGNOR TO HIMSELF AND LEVI HEYWOOD, OF SAME PLACE.

Letters Patent No. 73,720, dated January 28, 1868.

IMPROVEMENT IN WOOD-BENDING MACHINES.

The Schedule referred to in these Letters Patent and making part of the same.

TO ALL WHOM IT MAY CONCERN:

Be it known that I, MARTIN VAN BUREN HOWE, of Gardner, in the county of Worcester, and State of Massachusetts, have invented certain Improvement in Chains for Bending Wood, &c., of which the following is a full, clear, and exact description, reference being had to the accompanying drawings, making part of this specification, in which—

Figure 1 is a perspective view of my improved chain, the pieces at one of its ends being removed to show the manner of connecting the links together.

Figure 2 is a central vertical section through the same, with the end-pieces in place.

Figures 3, 4, and 5, details, to be referred to.

My invention relates to certain improvements in chains for bending heavy timber for various purposes, such as ship-building, &c., and consists in an improved method of connecting the links or sections of the chain in such manner as to insure great strength, and thereby prevent the liability of breaking incident to chains of this class as heretofore constructed.

To enable others skilled in the art to understand and use my invention, I will proceed to describe the manner in which I have carried it out.

In the said drawings, A A represent the links of a chain for bending heavy timber used in the construction of ships, buildings, bridges, &c. These links are of metal, and are made of considerable size and thickness, to insure great strength, and are of the form shown in fig. 1, in order that three sides of the timber to be bent may be surrounded, whereby not only the fibres of its outer surface are prevented from elongating, but its sides are confined so as to avoid any liability of bulging at the points where the greatest bend occurs. Each end of every link is cut or recessed out for the reception of the ends of connecting or coupling-links, or pieces, a, figs. 1 and 3, every two contiguous links, A, being united at each end by two coupling-links, a, which are loosely fitted in place, with a space, b, intervening between them, the upper link, a, lapping over the curved portions of the links a, on each side of it, by which construction, when the chain is bent, the links A are free to move in a horizontal plane upon the link a, connecting them in a manner similar to a ball-and-socket joint, and the inner surface of the chain assumes the degree of curvature intended to be given to the outer surface of the timber. Two circular plates, c, fig. 4, are placed in each recessed end of the links forming the extremities of the chain, to fill up the space between the curved portions of the alternate connecting-links a at this point, while all of the links a are prevented from springing out of place by solid pieces of metal, B, screwed to the links A, (see fig. 5,) the sides 6 of the pieces B fitting snugly over the ends of the links A, and affording additional strength. The sides 7 to 8 of each link A, are chamfered or bevelled off at such angles as to allow the inner line of the chain in contact with the timber to form a continuous unbroken surface when brought to the curvature desired, thus preventing the outer fibres from breaking.

I do not claim broadly a machine with flexible joints for bending wood, but

What I claim as my invention, and desire to secure by Letters Patent, is—

The coupling-links a, or their equivalents, for connecting the ends of the links A of a chain for bending timber, constructed to operate substantially as and for the purpose set forth.
